SPECTACLE FRAME OR THE LIKE

Jerrold W. Curry, Thompson, Conn., assignor to
 American Optical Company, Southbridge,
 Mass., a voluntary association of Massachu-
 setts

Application February 18, 1949, Serial No. 937

Term of patent 14 years

(Cl. D57—1)

To all whom it may concern:

Be it known that Jerrold W. Curry, a citizen of the United States of America, residing at Thompson in the county of Windham and State of Connecticut, has invented a new, original and ornamental Design for a Spectacle Frame or the Like, of which the following is a specification, reference being made to the accompanying drawings, forming a part thereof.

Fig. 1 is a perspective view of a spectacle frame, showing the essential features of my design in full lines;

Fig. 2 is a fragmentary front elevational view of the spectacle frame shown in Fig. 1; and

Fig. 3 is a side elevational view of the spectacle frame shown in Fig. 1.

My design as shown in full lines in the drawing is characterized by a ribbon-like band of color extending across the top portion of the bridge, the upper section of both rims, the temple end pieces and into the temples, and by a pair of long and slender members located within the confines of said ribbon-like band of color which follow the contour shape of the upper sections

of the rims on which each are disposed, and which are arranged to leave narrow margins of said band of color showing on their opposed sides.

I claim:

The ornamental design for a spectacle frame or the like, substantially as shown and described.

JERROLD W. CURRY.
